UNITED STATES PATENT OFFICE

JOHN A. BODKIN, OF NEW YORK, N. Y.

FLANGE AND RAIL LUBRICATOR

Application filed May 18, 1929. Serial No. 364,124.

This invention relates to improvements in flange and rail lubricators and has for one of its objects the provision of a device of the nature referred to at each end of a curve of a single track road and at the approaching end of a curve of a double track road, the said device consisting of a plurality of closed metal lubricating oil containers from which a wick projects upwardly and is adapted to engage the rail contacting surface of the car wheel flange, so that the oil is deposited on one corner and side of the curve to prevent rapid wear of the rail head.

Another object of the invention is to provide in a lubricating device of the nature referred to, a wick preferably made of wool felt and impregnated with particles of graphite, that will be carried upwardly by the oil to be deposited on the wheel flange and innermost portion of the wheel surface.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawing, in which

Figure 1 is a top plan view of one track of a double track road showing my invention as applied thereto.

Figure 2 is an end view of my improved lubricating device, partly in section and Figure 3 is a top plan view of one unit thereof.

Referring now to the drawing in detail 55 5 preferably indicates one track of a double track road, the said track comprising inner and outer track rails 6 and 7 respectively, which are curved as at 8. As the curved portion 8 of the outer rail 7 is raised above the 60 level of the curved portion on the inner rail 6, it is this outer curved portion that tends to turn the train and naturally gets the greatest amount of wear and therefore has to be lubricated to prevent excessive wear. To 65 accomplish this I secure to the bed road adjacent the inner edge of the outer rail 7 a lubricating device 9 which in the present instance comprises three closed receptacles 10 adapted to hold a quantity of lubricating oil 70 11. The combined length of the three receptacles 10 is equal to or slightly larger than the circumference of a train wheel. Immersed in the oil and extending from the 75 bottom of the receptacle 10 to the top or head of the rail and abutting the inner edge of the rail 7 there is a wick 12 preferably made of wool felt impregnated with suitably prepared particles of graphite 13. The said wick is supported between upstanding lips 80 or flanges 14 at the bottom of the receptacle and between similar flanges 15 and 16 at the top of the receptacle. The wick is bevelled at both ends thereof and extends substantially the entire length of the receptacles 10. 85 Openings 18 in the supporting base 19 of the receptacle provide means for securing same to the road bed by spikes 19a. Each receptacle is provided with an oil intake opening 20 at the top thereof, which opening is normally closed by a screw plug 21. A like plug 22 normally closes a drain outlet 23 at the bottom of the receptacles. While I prefer to impregnate the wick with graphite, I do not limit myself to do so, as I may use a 90 wick not so impregnated if I so desire.

If we assume that a train is coming in the direction of the arrow Fig. 1 it will be seen that the flange 25 of the outer wheels 26 will contact with the wick and have deposited 100

thereon a supply of oil or oil and graphite. Likewise the area on the circumference of the wheels 26 directly adjacent the flange 25 will also become coated with the lubricant 5 and when the said wheels pass over the curved portion 8 the lubricant will be transferred to the inner edge of the said curved portion and to the rounded portion 27 of the rail without spreading over the rail head.

- 10 From the foregoing it will be seen that I have provided a simple and efficient rail and flange lubricating device in which the lubricating oil is contained in a closed receptacle so that the supply of oil will not readily 15 evaporate or dry up or become clogged up with undesirable foreign matter.

Having described my invention what I claim as new and desire to secure by Letters Patent is:

- 20 1. In a rail and flange lubricating device, a normally closed lubricant container provided with a wick slot extending substantially the entire length thereof and tapered at the ends, flanges defining the edges of the 25 wick slot, flanges at the bottom of the receptacle in line with the first mentioned flanges, and a wick tapered at each end supported between the said flanges and extending through the slot to a predetermined height for the 30 purpose specified.
2. In combination with a curved rail, a lubricating device therefor, comprising a plurality of lubricant containers abutting each other, adapted to be placed adjacent the 35 inner edge of the rail and a wick tapered at each end extending substantially the entire length of each of the receptacles immersed into the lubricant and extending to a predetermined height above the receptacle for the 40 purpose specified.

In testimony whereof I hereunto affix my signature.

JOHN A. BODKIN.
